UNITED STATES PATENT OFFICE

CLIFTON CHISHOLM, OF CLEVELAND, OHIO, ASSIGNOR, BY MESNE ASSIGNMENTS, TO AMERICAN MULTIGRAPH CO., OF WILMINGTON, DELAWARE, A CORPORATION OF DELAWARE

PRINTING DEVICE

Application filed July 26, 1929. Serial No. 381,162.

This invention relates to a printing device of the general type wherein the various printing members, such as embossed strips, are mounted on a rotary drum and coact with a suitable platen, especially when such a device is in a simple form adapted for office printing. In many such instances the printing device is used for listing and other similar purposes wherein it is desired to replace a small number of the printing members or embossed strips, to bring the form up to date. In many instances, such as where the device is used for the listing of names, for example as in telephone directories wherein the data is constantly changing, it is necessary to have the form constructed in such manner that certain of the printing members may be readily removed and replaced to permit corrections to be made in the form from time to time.

An object of the invention is to provide a simple device whereby a form sheet, especially one comprising a list or other such data may readily be assembled.

Another object is to provide an improved printing form adapted to carry line units in the nature of individual printing strips wherein any one of the individual strips may be readily replaced without necessitating the removal of the other strips.

A further object is to provide a simple device wherein raised printing members, such as embossed strips may be mounted on a printing form, in such a manner that such strips may readily be removed and replaced without disorganizing the continuity or order of the remaining strips.

A further object is to provide a printing device wherein a form, such as a list, may be set up composed of printing members such as embossed strips in column formations.

In carrying out the invention I prefer to provide a suitable rotary drum having a removable segment adapted to carry the printing lines, which segment may be embraced by an inking ribbon carried by spools mounted in the drum, and such device may be adapted to coact with a rotary platen as the drum is rotated. The device accordingly partakes of the character of a multigraph printing

machine, except that instead of mounting the printing strips directly on the segment I mount each printing strip on an individual holder which in turn is adapted to be supported and locked in position on the segment. The individual holders and their respective printing strips may be divided into column formation by means of flat strips of less height than the holders, which flat strips extend arcuately about the surface of the segment and are provided with overhanging ribs adapted to engage the printing strip holders and retain them in position on the segment. By this means I am able to build upon the segment a tabular printing form accurately aligned, as well as one in which any one or more of the individual printing strips or lines may readily be removed without necessitating the removal or displacement of the remaining strips.

The features above referred to and other objects of my invention will be hereinafter more fully explained and become more fully apparent from the following description of the embodiment illustrated in the drawings. The essential characteristics thereof are summarized in the claims.

In the drawings, Fig. 1 is a side elevation of a printing device carrying my preferred form of printing strip and holder therefor; Fig. 2 is a cross section of the same as indicated by the line 2-2 on Fig. 1; Fig. 3 is a radial section indicated by the lines 3-3 on Fig. 2; Fig. 4 is a radial section of the segment illustrating retaining means for the printing strip holders, the position of which is indicated by the lines 4-4 of Fig. 2; Fig. 5 is a perspective on an enlarged scale of a printing strip with its associated holder, a portion of the printing strip being broken away; Fig. 6 is a vertical cross section indicated by the line 6-6 in Fig. 5; Fig. 7 is a development of the segment showing a tabular printing form mounted thereon and illustrating the manner in which a single line or strip may be removed. As this figure indicates it is well within the spirit of this invention that the strips may be mounted on suitable holders which in turn may be carried by a flat form for use in connection with standard flat bed

printing mechanisms. Fig. 8 is a perspective of one of the locking members; Fig. 9 is a perspective looking at the bottom side of another type of the locking member for the 5 form.

The printing device generally comprises as shown in Figs. 1 to 3 inclusive, a frame 10, a main shaft 11 journaled therein, and a crank 12 for rotating the shaft, a pair of 10 skeleton disks 13 which are secured to the shaft and are connected together by cross rods 14. The crank is shown rigidly secured to the shaft 11 and is adapted to drive a pinion 15 which meshes with the gear 16, rigidly 15 secured to one of the disks 13, which in turn is secured to the shaft 11.

The segment is generally designated 20 and comprises a wall portion extending for approximately a semi-circumference and provided on its exterior with grooves 20 and 21, the latter grooves being dove-tailed for the purpose of cooperating with suitable locking members. The segment is provided with overhanging ribs 24 which are bolted into 25 place on the segment to retain suitable printing strips as will hereinafter be described. The segment is also provided on its interior with transverse webs 23. Near the ends of the 30 inner surface of the cylindrical wall the segment bears on the rotary disks 13 while the webs 23 may bear on the cross rods 14. The segment may be held in place by spring hooks 30 pivoted to the segment by means of a rod 31 extending across the webs and at 35 its other end springing around the shaft 11.

The end disks 13 of the skeleton drum are shown as carrying a pair of ribbon spools 40 from which an inking ribbon 41 extends about the printing form. Such form coacts 40 with a rotary platen 45 which is mounted in the frame 12 and driven through by means of the gearing 15 and 16. The machine is accordingly adapted, when the crank is rotated, to print on paper fed between the drum 45 and platen.

The printing members comprise embossed strips 50 having a single row of upwardly extending characters 51 thereon and having the edges 52 of the strips extending away 50 from the embossed surface and inclining inwardly toward each other.

The embossed strips when produced are preferably straight and are made of a comparatively soft metal such as aluminum and 55 the characters thereon are accurately positioned so that the characters of one line may align with those of another, when the respective strips are aligned, which is very important. In tabular work I prefer to 60 mount the embossed strips on suitable individual supporting members or rails 60 which have an upwardly extending tongue which forms a head portion 61 adapted to be engaged by the down turned sides 52 of the 65 embossed strips. The supporting member

has a web portion 65 which joins the head to a suitable base portion 62 slightly greater in width than the printing strip so as to accurately space the strips and thereby the 70 printed lines. The ends of the strip holders or supporting members 60 extend somewhat beyond the embossed strip 50 and are cut away at the top thereof to form suitable lips 63 which are adapted to be engaged by suitable means mounted on the segment, such as 75 the overhanging ribs 24.

To retain the embossed strips and their associated holding members on the segment I prefer to mount the arcuate members 24 on the segment by means of suitable cap 80 screws as at 25. The members 24 have overhanging lips 66 adapted to overlie the ends 63 of the strip holders and retain the latter in contact with the outer surface of the segment. There may be a series of these arcuate 85 members 24; as illustrated in Figs. 1 and 7 I have shown three such members, in which instance the segment is accordingly divided thereby into two columns each of which is 90 adapted to carry a plurality of strip holders and their associated printing strips.

To retain the strips and their associated holders in position on the segment in such a manner as to prevent the shifting of the 95 holders on the segment I mount at one end of the segment suitable retaining blocks 70 each of which lie between two of the arcuate members 24 and extend substantially from one member to the other. The blocks 70 are 100 guided against angular movement on the segment by means of a boss portion 71 which is adapted to coact with the arcuate recesses 20 formed in the segment. To secure the retaining member 70 in position on the drum I prefer to employ suitable arcuate wedge 105 blocks 73 adapted to coact with the dove-tailed recesses 21 in the segment. Suitable screws 75, which pass freely through openings 76 in the member 70, are adapted to 110 coact with the wedges 73 and draw the latter tight against the converging sides of the arcuate grooves or recesses 21 of the segment, thereby securely clamping the members 70 in 115 position on the drum. It will be noted that, as these members are guided on the segment, they will serve to properly align the strip 120 holders and their associated embossed printing strips.

The holders carrying the embossed strips 125 are then laid in position on the drum much as indicated by the dotted lines at 60a on Fig. 7, wherein one of the extending ears 63 of a holder 60 has been inserted beneath the 130 extending portion or lip 66 of one of the arcuate members 24, the other ear 63 of the holder lying on the surface of the drum free from the adjacent arcuate member 24. The strip is then swung to the position as indicated by the 135 full lines at 60b in Fig. 7 wherein both of the 140

ears 63 are engaged by the overhanging projections 66 on the respective members 24.

To permit a comparatively tight fit between the portion 63 of the holders and the retaining member 24 the strip and associated holder may be slightly flexible to permit the unit to conform to the contour of the segment as the unit is swung into position.

To securely lock a number of printing strips on the segment I provide suitable blocks or locking lugs 80 as illustrated in Fig. 8 which have head portions 81 adapted to lie on the outer surface of the segment and which are lower in height than the printing strip supporting members 60 and which are adapted to engage sides 64 of the base of a supporting holder and retain the holder in position against the base next adjacent holder 60 and so on until the block 70 is reached. The locking member 80 has a suitable depending portion 82 adapted to coact with vertical portions 21a of the recesses 21 thereby serving to guide the block 80 against angular displacement on the form. A suitable wedge block 83, formed similar to the block 73 which cooperates with the member 70, is used for locking the member 80 in position on the segment. Suitable screws such as illustrated at 85 which pass freely through openings 86 in the members 80 and coact with threaded portions 87 in wedge blocks 83 serve to lock the member 80 and the grooved recesses 21.

The printing strips and their associated holders when assembled on the segment lie substantially in the position as illustrated by the left hand portion of the segment in Fig. 7. However, when it is desired to remove any one of the individual strips and its associated holder the clamping blocks 80 are slightly loosened from the segment and slid away from the holders to a position indicated at 80a in Fig. 7. If desired, the blocks 80 may be clamped in such position to prevent their inadvertent displacement. The printing strips between the holders and the strip which is to be removed from the segment are then shoved into position against the blocks 80a, as indicated at 60c, one end of the strip, which is desired to be removed, is then swung till the strip reaches approximately the position shown by dotted lines at 60b in Fig. 7, in which position the holder 60 has become free from one of the arcuate retaining members 24. The strip may then be slid laterally, thereby removing the strip from the remaining retaining member 24 and removing it from the segment. The strip may then be replaced with another, as heretofore described, or omitted entirely as desired. The operator may then move the strips 60c to a position where they contact with the balance of the strips and replace the blocks 80 in position to hold the strips rigidly against the block 70.

It will be seen from the foregoing descrip-

tion that I have provided a printing device which is adapted for use in connection with the printing of forms such as lists and the like, especially where it is desired to accurately align a plurality of lines in column formations and in which printing device any one or more of the individual lines of printing strips may be removed from the device and changed without necessitating the removal or disarrangement of the remaining strips or lines.

I claim:

1. In a printing device the combination of a long, narrow base strip having an upwardly extending rigid retaining device thereon, an embossed printing strip shorter than the base strip and having inwardly projecting edge flanges whereby the printing strip may be mounted on the base strip with the ends of the base strip extending beyond the printing strip and an arcuate printing member having parallel arcuate ledges overhanging the projecting ends of the base strip but with sufficient clearance to enable the printing devices to be skewed free from the ledges, said ledges forming abutments for the printing strips.

2. In a printing device, the combination of an arcuate segment, a plurality of embossed printing character strips, individual holders to support said strips, one holder for each strip, means comprising arcuate members secured to said segment adapted to retain the holders in contact with the outer periphery of said segment, said means adapted to restrain the strips from endwise movement, means associated with said segment adapted to retain the holders in contact with each other, both of said means being adapted to permit the removal of any one of said holders independently of the remaining holders.

3. In a printing device the combination with a segment having parallel arcuate strips thereon provided with overhanging portions, of a plurality of embossed printing strips having inwardly flanged edges, holders for said strips, said holders having head portions adapted to be embraced by the flanged edges of said printing strips, portions of said holders adapted to underlie said overhanging portions of said arcuate strips to retain them in contact with the form, while the arcuate strips provide abutments preventing removal of the embossed strips lengthwise without preventing skewing of the printing devices, and means abutting said holders adapted to retain them in contact with each other.

4. In a printing device, the combination of an arcuate segment, a plurality of embossed printing character strips, an individual holder associated with each strip, means extending arcuately on the segment adapted to retain the holders in contact with the segment and means associated with the segment

and abutting the extreme holders to retain the holders in contact with each other, both of said means lying below the printing portions of said embossed strips, said arcuate means comprising a pair of parallel strips spaced apart and radially overhanging the non-printing bodies of the embossed strips, said embossed strips being slightly shorter than the distance between the arcuate strips,
10 whereby the latter form abutments preventing material longitudinal movement of the embossed strips without preventing skewing of the printing devices.

5. In a printing device the combination of
15 a stiff arcuate segment, a plurality of embossed printing character bearing strips, an individual holder associated with each strip, which strip overlies and on which it is held by the inward edge flanges of the strip, both
20 said strip and holder being comparatively flexible, means extending arcuately on the segment adapted to retain the holders in contact with the segment while allowing their removal by skewing and means to retain the
25 holders in contact with each other.

6. In a printing device the combination of
a stiff arcuate support, a plurality of removable elongated flexible printing character bearing members adapted to lie parallel to
20 the support axis when in printing position, means extending arcuately on the support adapted to overlie the ends of the members to retain them in printing position in contact with the support, such flexibility permitting
35 the members to be turned askew and warped to conform to the support whereby said members may be individually assembled onto the support between other members notwithstanding the curvature of the support.

40 In testimony whereof, I hereunto affix my signature.

CLIFTON CHISHOLM.
